UNITED STATES PATENT OFFICE

2,118,833

LIGHTING FIXTURE

George Arras, Chicago, Ill.

Application December 18, 1936, Serial No. 116,531

8 Claims. (Cl. 240—143)

This invention relates in general to an electric lighting fixture and has more particular reference to a combined socket and shade support.

An important object of the invention is in the provision of a combined socket and shade support which is simple in construction and operation, in which the same fastening means is operative both to attach the socket and shade in position and to release the shade for disengagement or removal without releasing the socket.

A further object of the invention is in the provision of an improved yielding support for a socket in which the socket is easily and quickly removed or disengaged from its normal lamp supporting position in a holder.

A still further object of the invention is in the provision of fastening means inserted at the sides of a holder for releasably clamping a shade in position and for also supporting a socket in the holder.

Other objects of the invention will appear hereinafter, the preferred structures being shown in the accompanying drawing in which

Fig. 1 is a side elevation of a fixture with a support and an angle shade in accordance with the principles of this invention;

Fig. 2 is an enlarged sectional view of the holder and supporting means taken on the line 2—2 of Fig. 1;

Fig. 3 is a sectional view taken on the line 3—3 of Fig. 2;

Fig. 4 is a view partly in section as taken on the line 4—4 of Fig. 2;

Fig. 5 is a sectional view similar to Fig. 3, of a modification; and

Fig. 6 is a view partly in section as taken on the line 6—6 of Fig. 5.

In an electric fixture the common arrangement and construction is to provide a cap or holder usually threaded in position at the end of a pipe or other support, to attach a socket in this holder by means of screws inserted through the socket, and to separately attach a shade to the holder by other fastening means. If the socket fastening screws are inserted through the bottom they are difficult of access and the screws are not easily engaged with corresponding threaded portions in the holder; or if the fastening screws extend through projections at the sides of the socket, these projections are easily broken or damaged by the insertion of the fastening means.

In the present invention all these difficulties are overcome, it is unnecessary to provide threaded holes in the holder, and the fastening screws or

other means are easily engaged or inserted from the sides of the holder and are not threaded into the holder itself.

Referring now more particularly to the drawing, a supporting cap or holder 10 has a threaded opening, usually at the upper end, for receiving a supporting pipe 11 with a depending bottom flange 12 and one or more offset shouldered portions 13 and 14. Of these shouldered portions the latter provides an abutment for the upper end of a lamp socket 15 and the upper shouldered portion 13 provides a space for accommodating conductor wires 16 which are attached to the terminals 17 and 18 of the lamp socket in a well known manner.

The socket is adapted to receive an electric lamp 19 and has a flange or base extension 20 of a size to be received by the shouldered portion 14 with recesses 21 at the inner or upper sides to seat opposite compressed springs 22 which are adapted to bear against the shouldered portion 14.

A shade holder or reflector 23 has a reduced supporting neck 24 with a flange 25 at its upper end and adapted to fit within the flange 12 of the holder. A gasket or washer 26 is preferably inserted between the flange 25 and a shoulder 27 within the flange of the holder for preventing damage to the flange of the shade holder and the inner opening 28 of the shade holder may therefore be of such a size that the socket 15 with its flange 20 may be inserted through the opening 28.

At opposite sides of the holder 10 are clamping plates 30, each of a length to fit against the shoulder 14 at its inner end and beyond the shoulder 27 at the outer end. The outer end of each clamp has an outwardly extending curved rim or projection 31 adapted to engage below or within the opening 28 of the holder 24 and against the inner edge of the flange 25. Intermediate the ends of each plate is a threaded opening 32 through which a fastening screw 33 is inserted from the outside of the holder 10 through an unthreaded opening 34 in the wall thereof so that by threading the screw inwardly the clamping plate 30 is drawn outwardly into engagement with the flange 25 of the shade holder. Each fastening screw 33 is sufficient in length to extend beyond the plate and at the outer side of the flange 20 of the socket when it is inserted in the holder 10 against the shoulder 14 with the springs 22 partially compressed. By pressing the socket inward and slightly compressing the springs 22 the ends of the screws 33 will engage over the outer faces of the flange 20, thereby confining the

socket in the holder and yieldingly supporting it by means of the springs 22. Thus the same screws which bind the shade holder in place may be extended to releasably lock the socket in place 5 and the socket is yieldingly supported in the holder by the springs.

In order to accommodate the clamping plates at the sides of the socket, recesses 35 are provided of the length or arcuate extent of the 10 plates 30, and near the center is a further recess 36 for accommodating the inner end of each screw 33 and allowing the flange 20 to pass the end of the screw without withdrawing the screw entirely from or flush with the inner surface of 15 the clamping plate 30. The inner end 37 of each fastening screw 33 may be slightly upset or the threads damaged after their insertion through the plates 30 so that they are not easily withdrawn through the plates after once being placed 20 within the holder 10.

The above structure is somewhat yielding in one direction to flexibly support the socket and a lamp held thereby, and in the structure shown by Figs. 5 and 6 the socket is made more flexible 25 by providing opposite recesses 40 in the flange of the socket, each of which has a leaf spring 41 extending thereover and secured by a fastening screw 42 at one side of the recess so that the other end will be free to flex in the recess. The 30 lower or outer face of this leaf spring is engaged by the inner end of the fastening screw 33 for retaining the socket in position but permitting a more flexible movement of the socket in the holder and thus protecting the lamp carried by 35 the socket against vibration. In this form, as in the other, the socket is retained in place by the same screws which bind the reflector support in place and the springs 22 tend to press the socket outwardly from the holder. The socket is thus 40 flexibly supported within the holder by the springs 22 at one side and by the leaf springs 41 at the other side.

In both forms as shown, the inner ends of the same screws which are inserted through the 45 shade or reflector clamping plates 30 are extended to hold the socket in place. In order to remove the reflector or shade holder from the holder 10 it is necessary only to back off the screws 32 a slight distance, releasing the clamping plates which have a sufficient movement between their inner ends and the recesses 35 of the socket to give them a slight freedom of movement, such that the inner flange 25 of the shade 50 holder 24 may be disengaged from the clamping plates for bodily removing the shade holder. A continued releasing movement of one or both of the fastening screws 33 will free one or both sides of the socket 15 so that the edge recess 36 will slip by the inner end of one of the screws 33, 55 allowing the socket to be disengaged from the holder for repair or attachment. There is no tendency for the socket to stick in the holder as the springs 22 tend to force them outwardly after either side is free from engagement with the 60 holding screw 33, and in practice the socket is usually slipped out after loosening the screws and disengaging one side so that the end of the screw 65 will pass through the opening 36 thereof.

By having the fastening screws 33 inserted 70 from the sides they are easily accessible, no difficulty is experienced in inserting fastening screws through the socket and into the holder, and it is not necessary to provide the holder with threaded openings, for engaging the fastening screws.

75 Various changes in structure may be made

without departing from the spirit and scope of the invention. For example this structure although described in connection with a socket having a projecting base flange, may also be applied to a larger socket in which the ends of the 5 screws 33 engage in opposite recesses in the socket itself.

I claim:

1. In a lighting fixture, a support, a shade holder having a flange extending into the support, a lamp socket inserted in the support, a clamping plate within the support having an outer projection to engage the flange of the shade holder, and fastening means inserted through the support and the clamping plate for binding 10 the shade holder in place, the inner end of the fastening means also engaging the socket for confining it within the holder.

2. In a lighting fixture, a support, a lamp 15 socket inserted in the support, a shade holder surrounding the lamp socket and having an inwardly extending flange at its upper end, opposite clamping plates inserted between a socket and a support, and having an outer projection to engage the flange of the shade holder, and fastening screws inserted through the sides of the support threaded through the clamping plates and engaging the socket to confine both the socket and the shade holder within the support.

3. In a lighting fixture, a support, a lamp 20 socket having a base projection and fitting within the support, fastening means for the socket comprising a screw extending loosely through an opening in the side of the support, a threaded member between the socket and the support 25 through which the screw extends, and the end of the screw engaging the outer side of the projection the socket for holding it in the support.

4. In a lighting fixture, an internally shouldered support, a socket fitting within the support 30 and having springs in the base to fit against a shoulder therein, fastening means inserted through the outer opposite sides of the support and engaging the outer side of the socket so that the springs tend to hold the socket against 35 the ends of the fastening means.

5. In a lighting fixture, a support, a socket 40 having a base flange with recesses at the inner side thereof, springs seated therein but projecting from the surface of the base, fastening means 45 inserted through the opposite edges of the support and adapted to engage the outer base of the flange when the socket is pressed outwardly from the holder by the springs.

6. In a lighting fixture, a support having a projecting edge, a shade holder having a flange seated in the edge of the support with an end opening and an inwardly turned flange, and fastening means for confining the holder within the support comprising a plate with an outwardly 55 extending projection to engage within the flange of the holder and a screw threaded from the edge of the support into the plate for drawing the projection outwardly against the flange.

7. In a lighting fixture, a support, a shade 60 holder to fit within the support having an opening in the end and an inwardly turned flange at the edge of the opening, a clamping plate extending within the support at each side having a projection to extend within the opening of the 65 holder and against the flange thereof, a fastening screw inserted through the edge of the support and threaded through each clamping plate for drawing it tightly against the flange of the holder and a socket within the opening and at 70 75

the inside of the plates engaged by the inner ends of the screws, the shade holder being disengaged by releasing the screws so it can be bodily removed without disengaging and removing the socket from the support.

5. 8. In a lighting fixture, a support, a socket fitting within the support having a projection with recesses at the bottom and also with side re-

cesses, springs within the bottom recesses to abut the inside of the support, leaf springs attached to the socket and overlying the other recesses of the flange, and fastening means inserted through the edge of the support and in engagement with the leaf springs for holding the socket flexibly between the springs within the support.

GEORGE ARRAS.
